UNITED STATES PATENT OFFICE.

STEWART CHRISMAN, OF WATERLOO, NEW YORK.

PICKER MOTION FOR LOOMS.

Application filed December 8, 1924. Serial No. 754,628.

To all whom it may concern:

Be it known that I, STEWART CHRISMAN, a citizen of the United States of America, of Waterloo, in the county of Seneca, in the 5 State of New York, have invented new and useful Improvements in Picker Motions for Looms, of which the following, taken in connection with the accompanying drawings, is a full, clear, and exact description.

10 This invention relates to a picker motion for looms, and refers more particularly to the means for regulating the power and stroke of the picker staff for driving the shuttle through the shed.

15 These picker sticks or staffs are usually operated with a parallel motion through the medium of a power driven sweepstick or operating bar having a terminal lug strap loosely engaging the picker staff for lengthwise adjustment thereon to vary the power and stroke as may be required to impart the desired movement of the shuttle through its guide.

20 It is found, however, that when the lug strap and its operating bar are adjusted as a unit, the line of draft of the lug-strap is frequently abnormal to the longitudinal edge of the picker staff and that under such conditions, even though it may be initially set to impart the desired power and stroke to the shuttle, its tendency is to shift more or less toward a position normal to the picker staff which results in varying the power and stroke, destroying the proper synchronism 25 of action with relation to the decussation of the warp, and subjects the picker staff to more or less excessive strains, all of which reduces the efficiency of the machine, and in some instances is the direct cause of breaking 30 the picker-staff and unduly wearing the lug strap.

The main object of the present invention is to obviate these objectionable results by 35 providing a more easily adjustable clamp connection between the lug-strap and its operating bar, and to cause said connection, when tightened, to more firmly hold those parts in their adjusted position relatively to said bar.

40 Another object is to support the clamp for the lug-strap directly upon an upright arm which is fulcrumed co-axially with and extends upwardly along the picker staff so that the weight of the lug-strap and adjacent 45 end of the operating bar together with the clamp will be transmitted through the arm

directly to the pivotal fulcrum common to both the arm and staff, and thereby to further assist in holding the lug-strap in any position to which it may be set. 60

Other objects will be brought out in the following description:

In the drawings:—

Figure 1 is a side elevation of a picker motion for the multiple box side of a loom, the dotted lines indicating different positions to which the staff may be set. 65

Figures 2 and 3 are enlarged detail sectional views taken respectively on lines 2—2 and 3—3, Figure 1. 70

Figure 4 is a face view of the detached coupling clamp for connecting the lug-strap, and its operating bar to the upright arm, and for holding the lug-strap in its adjusted position relatively to said bar. 75

Figure 5 is a side elevation of a picker-motion, as used on the single box side of the loom.

Figures 6 and 7 are enlarged sectional views taken respectively on lines 6—6 and 7—7, Figure 5. 80

Figure 8 is a perspective view of the bracket for connecting the parallel motion to the staff.

In both of the picker motions shown in Figures 1 and 5 an upright arm —1— is fulcrumed coaxially with the staff —2— by means of a pivotal bolt —3— which is common to both of those parts and permits them to rock about the same axis, the arm —1— extending upwardly along one side of and in sufficiently spaced relation to the staff to receive one side of the lug-strap —4— between them. 85

The lug-strap —4— preferably consists of one or more layers of heavy leather bent U-shape to embrace the adjacent portion of the staff —2—, and has its ends overlapping upon opposite sides of an operating bar —5— and pivotally connected thereto by a pivotal bolt —6—. The operating bar —5— may be actuated by any suitable means, as for example, a crank arm —7— on a suitable rock-shaft —8— which is power-driven by any well-known means, the other end of the bar being adapted to receive the lug strap —4— and pivotal bolt —6—, and coupled to the upper end of the arm —1— by means of a clamping plate —9— having one end apertured for receiving the clamping bolt —6— and its other end provided with a pivotal stud —10— adapted to enter 95 100 105 110

any one of a plurality of holes —11— in the adjacent portion of an arm —1—, whereby the lug-strap —4— and adjacent end of the operating bar —5— may be adjusted vertically along the power stick —2— and held in any one of its adjusted positions by the engagement of the lug 10 in one of the apertures —11—, which latter are arranged in vertically spaced relation lengthwise of the arm 1.

The end of the clamping member —9— which is mounted upon the pivotal bolt —6—, is provided with a serrated inner face —12— adjacent the corresponding side of the lug-strap —2—, the serrations —12— being preferably radial and arranged about the axis of bolt —6—, and also raised or embossed to impress themselves into the adjacent face of the lug-strap —4— when the bolt —6— is tightened.

In other words, the lug-strap —4— and clamping plate —9— are relatively adjustable angularly about the axis of the pivotal bolt —6—, while both of these parts are also adjustable angularly about the same axis relatively to the operating bar —5— by simply loosening said bolt, but when the lug-strap and clamping plate are adjusted to the proper position to impart the desired power and stroke to the staff —2—, the bolt may be tightened to hold the lug-strap and clamping plate in their adjusted positions.

This independent angular adjustment of the clamping plate —9— and lug-strap —4— about the axis of the bolt —6— permits the clamping plate to be engaged in any one of the apertures —11— of the arm —1— and also permits the lug-strap to be adjusted more nearly normal to the longitudinal center of the staff.

Any suitable mechanism as A, Figure 1, or A', Figure 5, may be employed for supporting the pivotal bolt —3— for the staff —2— and arm —1—.

The picker motion, as shown in Figures 6 to 8 inclusive is substantially the same as that shown in Figures 1 to 4 inclusive, except that it is to be used at the single side of the loom, and the same reference numerals apply to both devices. In Figure 5 however, the upper end of the picker stick is shown as provided with a plurality of layers —13— of leather forming the usual more or less resilient contact-member for engaging and operating the shuttle along its guide, and across the web.

What I claim is:

1. In a picker motion for looms, a picker-staff and an upright arm both fulcrumed to

swing about one and the same axis, a lug-strap loosely embracing the picker-staff, an operating bar to which the lug-strap is pivoted for angular adjustment thereon, means for reciprocating said bar and lug-strap for oscillating the picker-staff, and a clamping plate pivoted to said bar and to the adjacent ends of the lug-strap coaxial with the axis of movement of the lug-strap and interlocking connections between said clamping plate and arm.

2. In a picker motion for looms, a picker-staff and an upright arm both pivoted to swing about a common axis, the said arm being extended along one side of the picker-staff in spaced relation thereto and provided with a plurality of apertures in longitudinally spaced relation, a reciprocally movable operating member adjustable lengthwise of said arm a coupling clamp having one end pivoted to said member and its other end provided with a pivotal stud engaging in one of the apertures of said arm for transmitting motion thereto, and a lug-strap operatively connected to said member and embracing the picker-staff for imparting motion thereto.

3. In a picker motion for looms, a picker-staff and an upright arm both pivoted to swing about a common axis, said arm being extended along one side of the picker-staff in spaced relation thereto and provided with a plurality of apertures in longitudinally spaced relation, a reciprocally movable operating member adjustable lengthwise of said arm, a coupling clamp having one end pivoted to said member and its other end provided with a pivotal stud engaging in one of the apertures of the said arm for transmitting motion thereto, a lug-strap operatively connected to said member and embracing the picker-staff for imparting motion thereof, said coupling clamp and lug-strap being movable about a common axis relatively to said operating arm.

4. In a picker motion for looms, a picker stick, an operating bar, a lug strap pivoted to the bar for angular adjustment relatively thereto, clamping means for holding the lug strap in its adjusted position including a clamping plate mounted upon and adjustable to different angles relatively to the bar, and a supporting arm for the clamping plate operatively connected to the picker staff to move therewith.

In witness whereof I have hereunto set my hand this 22nd day of November 1924.

STEWART CHRISMAN.
